EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

1,309,226.

Specification of Letters Patent.

Patented July 8, 1919.

Application filed April 13, 1918. Serial No. 228,312.

To all whom it may concern:

Be it known that I, EDWARD S. STIMPSON, of Hopedale, in the county of Worcester and State of Massachusetts, have invented 5 a new Feeler Mechanism for Looms, of which the following is a specification.

The new feeler mechanism includes a feeler of the type which tends to move lengthwise of the bobbin but which is restrained from such lengthwise movement by the weft on the bobbin, the lengthwise movement occurring when the weft approaches exhaustion, the feeler then encountering and slipping along the smooth 10 surface of the bobbin. The new feeler mechanism is so organized that it presents a mechanism of simple construction involving but little strain upon the bobbin and preventing any damage to or cutting of the 15 weft.

The new feeler mechanism is illustrated in the accompanying drawings in which—

Figure 1 is a plan view. In this figure the bobbin is shown just as the weft first encounters the feeler tip during the forward swing of the lay. Fig. 2 is a vertical section in the plane indicated by the line 2—2 in Fig. 1. Fig. 3 is a plan view illustrating the feeler and the bobbin in the positions 20 which they occupy when the lay is all the way forward and there is a substantial amount of weft on the bobbin. Fig. 4 is a plan view showing the relative positions of the bobbin and the feeler when the lay is all 25 the way forward and the feeler has slipped lengthwise of the bobbin and has moved laterally the controller which initiates the 30 action of the train of weft-replenishing mechanism. Fig. 5 is a vertical section in 35 the plane indicated by the line 5—5 in Fig. 1. Fig. 6 is a vertical section in the plane indicated by the line 6—6 in Fig. 1. Fig. 40 7 is a vertical section illustrating the rocking support for the front end of the feeler. 45 Figs. 8, 9, and 10, are enlarged views of the feeler tip illustrating, respectively, the initial contact between the weft and the feeler tip, the full contact between the weft and the feeler tip, and the contact between the 50 bare bobbin and the feeler tip. Fig. 11 is a vertical section of the feeler tip and the forward end of the feeler arm.

The feeler comprises a feeler arm A, and

a feeler tip B, pivotally connected therewith by pivot screw C, as shown in Fig. 11. The 55 rear end of the feeler arm is forked to receive the feeler tip. The feeler tip has a plurality of teeth D, (five being shown), and these teeth are blunt and rounded at their ends so that they do not cut or injure the 60 weft when brought into contact therewith. The feeler tip may be made of metal or of vulcanized fiber such as is frequently used for electrical insulation. The feeler tip is 65 loosely and freely pivoted to the feeler arm and is free to move with respect to the feeler arm within the limits determined by the corners E, of the tip and the wall F, of the feeler arm which constitutes a stopping 70 means for the tip. By reason of these limitations to the swing of the feeler tip it can never swing far enough to carry its teeth out of the range of action of the bobbin or weft-carrier G, or of the weft H, wound thereon. By reason of the free unrestrained swing of 75 the feeler tip on the feeler arm unaffected by a spring, the feeler teeth always accommodate themselves to the weft or the bobbin. For example, assuming the tip to occupy the position shown in Fig. 8, at the first contact 80 between it and the forwardly moving weft, the tip will then swing on its pivot C, as the weft continues to advance so that all of the teeth will accommodate themselves to the surface of the weft and uniformly contact 85 therewith, as shown in Fig. 9, and this irrespective of whether or not the outer surface of the weft is parallel with the surface of the bobbin or not. Likewise, when the bobbin 90 is bare opposite the feeler tip, all of the teeth will contact with the surface of the bobbin and slide lengthwise thereof, as indicated in Fig. 10, so that there will be no digging into the surface of the bobbin or marring thereof.

The feeler arm A, is mounted on a stationary feeler support consisting of a bracket I, attached to a lateral extension J, of the breast beam. A guide K, is swiveled to the forward end of the feeler-support, turning on a vertical axis. This 95 guide has a through-aperture through which the feeler arm near its front end extends and slides as shown in Figs. 1, 3, 4, and 7. Near its rear end the feeler arm extends through a broad passageway or slot L, of 100 105 a slotted guide at the rear of the feeler

support, as shown in Figs. 3 and 4. The top of this passageway or guide-slot is closed by a cap M, as shown in Figs. 1 and 5, thus confining the feeler arm against vertical movement. Secured to the feeler arm near its middle is a slide N, which slides on horizontal slideways O. of the feeler support. This slide screws upon the feeler arm for adjustment as shown in Fig. 3, 10 and is held in place by nut P. A spring Q, surrounds the feeler arm between nut P, and rock shaft K, and normally holds the feeler arm in its rearward position as shown in Fig. 1, with the slide N, against the spaced lugs R, and S, at opposite sides of the passageway L, and with the feeler arm against the rearwardly extending face of the outer lug R, as shown in Fig. 1. In this normal position the feeler arm extends 15 at an angle to the fore and aft path of the lay T, and hence is inclined to the longitudinal axis of the shuttle and of the weft-carrier. Also, the forward end of the arm is bent to the right at U, as shown in Fig. 25 1. As a result of this lateral bend of the forward end of the feeler arm and the inclination of the arm to the path of the lay, the weft on the bobbin encounters the feeler tip out of line with the lug R, and 30 the swiveled guide K. In other words, the swiveled guide is offset laterally and outwardly with respect to the feeler tip so that the bobbin encounters the tip along a fore and aft path nearer the tip of the 35 bobbin than a parallel path intersecting the guide. Consequently, as the shuttle in the box at the detecting end of the lay moves forwardly, the impact or frontward push of the advancing bobbin on the feeler tip 40 tends to move the same longitudinally of the bobbin; and, as illustrated, inwardly away from the butt of the bobbin and toward its tip. As long as the weft on the bobbin encounters the teeth of the tip, the 45 resistance thus offered prevents any slipping of the tip lengthwise of the bobbin. Accordingly, as the lay at each detecting beat moves forward after the first encounter of the weft with the tip there is no sliding 50 of the tip on the weft; but during this completion of the forward movement of the bobbin the feeler arm is moved forwardly compressing the spring Q, as shown in Fig. 3. During this normal action, there is a 55 slight inward swing (to the right) of the feeler arm as indicated in Fig. 3 which shows the feeler arm moved inwardly a short distance away from the rearwardly extending face of the lug R. This normal 60 swing of the feeler arm is permitted because its front end slides in the guide K, which turns sufficiently to accommodate the swing of the feeler arm, and because near its rear end it plays in the slotted rear guide. When the lay retreats the spring 65

Q, carries the feeler arm backwardly until the slide N, again encounters the lugs R, and S.

In the event, however, that the weft is nearly exhausted so that the bare surface 70 of the bobbin encounters the feeler tip, the tip is no longer restrained by contact with the weft but slips along the smooth surface of the bobbin away from its butt and toward its tip as indicated in Fig. 4, the several 75 teeth of the tip riding along all in contact with the bobbin. This involves a still further inward lateral swing of the feeler arm to the right and this additional swing is functional to set into action the train 80 of weft-replenishing mechanism. During this functional swing of the feeler arm the feeler arm also moves forwardly to a limited extent during the completion of the forward movement of the lay as indicated 85 in Fig. 4, thus carrying the slide N, forwardly of the lugs R, and S, as indicated in Fig. 4. It will be noted that the passageway or slot L, between the lugs is wide 90 enough to permit this functional swing of the feeler arm. When the lay with the bared bobbin retracts, the spring Q, carries the feeler arm backwardly and a depending lug V (Fig. 5) on the slide N, encounters a fixed restoring cam W, on the 95 bracket thereby restoring the feeler arm to its normal position against the rearwardly extending face of the lug R.

The normal idle position of the tip is such that a portion of the weft still remains 100 on the bobbin, as shown in Fig. 4, when the bared bobbin encounters the feeler tip so that enough weft remains to last until the replenishment of weft has been effected.

The functional swing of the feeler arm under the impact of the bared bobbin on the feeler tip is utilized to set into action the train of weft replenishing mechanism. This train of mechanism includes a controller X, 105 which is mounted in a transverse guideway Y, formed in the lugs R, and S, as shown in Figs. 3 and 4; and beneath the cap M, as shown in Fig. 2. The controller has a slot Z (Figs. 2, 3 and 4) through which the feeler arm extends. This slot is sufficiently wider 110 than the width of the feeler arm, as shown in Fig. 2, so that the normal swing of the feeler arm (see Fig. 3) has no effect upon the controller. When, however, the functional swing of the feeler arm is imparted to it by 115 the lengthwise movement of the feeler tip along the bobbin due to the impact of the bare bobbin the controller is slid laterally inward (to the right) as shown in Fig. 4. This lateral movement of the controller is 120 utilized to bring about weft replenishment. A connecting rod 11, is pivoted at its outer end to the controller as shown in Figs. 3 and 5, and at its inner end it is adjustably connected with the lower arm of a lever 12, 125 130

which is pivoted at 13, to a stationary arm 14. This lever has a horizontal arm 15, Figs. 1, 5, and 6, constituting a lifter which extends beneath a finger 16, of a latch 17. 5 This latch is pivoted at 18, to a transmitter 19, which at its forward end is pivoted at 20, to a crank arm 21, fast on the starting shaft 22. This rocking starting shaft corresponds in action and function with the shaft 10 ^d of the United States Letters Patent of Northrop 529,940, November 27, 1894. The transmitter 19, has a depending foot 23, (Fig. 6) resting upon the horizontal surface of the breast beam extension J. The latch 17, has a dagger 24, (Figs. 1 and 6) which normally is in a plane below an overhanging bunter 25, on the upper end of the usual weft hammer 26.

During the normal running of the loom 20 the weft hammer bunter 25, reciprocates idly above the dagger 24. When, however, the weft in the running shuttle approaches exhaustion and the bobbin is bared opposite the feeler tip B, with the consequence that 25 the feeler tip under the impact of the bobbin moves lengthwise thereof, the controller X, is moved inwardly (Fig. 5) thereby through rod 11, swinging the lever 12, thereby lifting the rear end of the latch 17, and bringing the 30 dagger 24, up into the path of the bunter 25. The weft hammer is so timed with respect to the beat of the lay that this upward lift of the dagger 24, occurs as the weft hammer is moving forwardly and has approximately 35 reached the position shown in Fig. 6. During the subsequent forward movement of the weft hammer its bunter 25, encounters the dagger 24, and carries the same forwardly with it, thus likewise moving forwardly the 40 transmitter 19, and the crank arm 21, thereby rocking the starting shaft 22. The rocking of this starting shaft brings about the replenishment of the weft in a well known way; as, for example, by the bobbin changing mechanism set forth in said Northrop 45 Patent No. 529,940. Consequently the weft is replenished before the running weft is entirely exhausted.

When the weft hammer again moves backwardly the starting shaft 22, and the arm 19, are restored to their normal positions, as 50 shown in Fig. 6, in any well known way as, for example, by a spring, such as the spring ^c of United States Letters Patent of Northrop No. 529,940, November 27, 1894. When the lay moves backwardly carrying the bobbin beyond the feeler tip, the spring Q, and the cam W, restore the feeler arm A, to the position shown in Fig. 1. During this 55 restoration movement, the feeler arm carries the controller X, outwardly (to the left) to the position shown in Fig. 1, and the lifter 15, is lowered. Thereupon the latch 17, drops by gravity at its rear end thus bringing the dagger 24, to the position shown in

Fig. 6, below the path of the weft hammer bunter 25.

The construction of this new feeler mechanism is simple. The feeler arm is light in weight so that the spring Q, can be of minimum strength. Accordingly only a light strain is brought upon the bobbin due to the impact thereof against the feeler tip. Also this is the only spring employed in the feeler mechanism, the dagger 24, dropping by 75 gravity. Consequently, there is no careful adjustment rendered necessary in order that two or more springs may properly coöperate. This spring acts following every detecting beat of the lay to move the feeler rearwardly, 80 and after the feeler has been displaced laterally and has initiated the action of the weft replenishing mechanism this spring also acts to move the feeler laterally to its normal 85 feeling position.

The feeler arm is pivotally supported at its front end remote from the feeler tip, so that it swings through a small arc when the tip slips on the bobbin, and through a smaller arc during the normal running of the 90 loom. Hence, the tip slips along the bared bobbin with its teeth parallel thereto since the concurrent advance of the bobbin compensates for the swing of the feeler arm. The bend U, in the rear part of the feeler 95 arm simply increases the lateral offset of the tip with respect to the rock-shaft thereby increasing the effect of the impact of the bobbin to displace the feeler arm laterally; and it has no other office. The free swing of the 100 tip simply causes the teeth to accommodate themselves to the surface of the weft and of the bobbin; and it occurs while weft is present as well as when the bobbin is bare.

The organization is such that the feeler 105 tip slips inwardly along the bare bobbin from the butt to the tip thereof. Hence, when the tip starts to slip it completes its movement, as there is no weft in its path to stop its movement.

While this feeler mechanism is intended more particularly for setting into operation a train of weft replenishing mechanism in a bobbin changing loom, it is obvious that it 110 can likewise be employed in a shuttle changing loom or for stopping the loom.

I claim—

1. A loom having, in combination, a feeler arm with a tip in the path of the weft when in the box at the detecting end of the lay; a swiveled guide slidingly supporting the front end of the feeler arm, said guide being offset laterally and outwardly with respect to the feeler tip so that the bobbin 120 encounters the tip along a path nearer the tip of the bobbin than a parallel path intersecting the guide whereby the impact of the weft on the feeler tip tends to swing the feeler arm inwardly; stationary lugs spaced apart to provide an enlarged passageway 125 130

- for the feeler arm; a slide on the feeler arm; a spring which normally holds said slide against said lugs; a stud projecting from said slide; a stationary restoring cam coöperating with said stud; a laterally movable controller having a slot through which the feeler arm freely passes during the normal running of the loom, said controller being moved inwardly when the feeler arm moves laterally due to the slipping of the feeler tip along the bared bobbin; and a train of mechanism brought into action by the lateral movement of the controller.
2. A loom having, in combination, a feeler arm with a tip in the path of the weft when in the box at the detecting end of the lay; a swiveled guide slidably supporting the front end of the feeler arm, said guide being offset laterally with respect to the feeler tip so that the weft encounters the tip along a path laterally different from a parallel path intersecting the guide whereby the impact of the weft on the feeler tip tends to swing the feeler arm; stationary lugs spaced apart to provide an enlarged passageway for the feeler arm; a slide on the feeler arm; a spring which normally holds said slide against said lugs; a stud projecting from said slide; a stationary restoring cam coöperating with said stud; a laterally movable controller having a slot through which the feeler arm freely passes during the normal running of the loom, said controller being moved inwardly when the feeler arm moves laterally due to the slipping of the feeler tip along the bared bobbin; and a train of mechanism brought into action by the lateral movement of the controller.
3. A loom having, in combination, a sliding and swinging feeler arm with a tip in the path of the weft when in the box at the detecting end of the lay, said tip being laterally offset with respect to the front end of the feeler arm, so that the impact of the weft on the feeler tip tends to swing the feeler arm; a spring which moves the feeler arm rearwardly; a laterally movable controller having a slot through which the feeler arm freely passes during the normal running of the loom, said controller being moved laterally when the feeler arm moves laterally due to the slipping of the feeler tip along the bared bobbin; and a train of mechanism brought into action by the lateral movement of the controller.
4. A loom having, in combination, a sliding and swinging feeler arm with a tip in the path of the weft when in the box at the detecting end of the lay; a laterally movable controller which is idle during the normal running of the loom, but which is moved laterally when the feeler arm moves laterally due to the slipping of the feeler tip along the bared bobbin; and a train of mechanism brought into action by the lateral movement of the controller, including a weft-hammer with a bunter, a gravity latch with a dagger normally out of the path of said bunter, a lever having an arm coöperating with said latch, and a rod connecting said lever and said controller.
5. A loom having a feeler mechanism, comprising, in combination, a feeler supported to enter the shuttle in a direction inclined to the longitudinal axis of the weft-carrier and movable in a direction inclined to the path of the lay, but being held from movement lengthwise along the weft-carrier by the weft on a detecting beat until approaching exhaustion thereof and then moving along the weft-carrier by the impact of said carrier, and means actuated by the feeler to initiate filling replenishment when the weft approaches exhaustion.
6. A loom having a feeler mechanism, comprising, in combination, a feeler supported in a position and for movement inclined to the path of the lay on each detecting beat, said movement being in a direction inclined to the lay, and held from movement along the weft carrier under the impulse of the impact of the weft until approaching exhaustion thereof, and means supported for actuation by the feeler when the latter is moved along the weft-carrier by the impact of the weft-carrier for changing the operative condition of the loom.
7. A loom having a feeler mechanism having, in combination, a feeler support, a feeler that is mounted to slide in an inclined direction upon the support and that is held from movement lengthwise along the weft-carrier on a detecting beat by engagement with the weft until approaching exhaustion thereof and is then laterally displaced along the weft carrier by impact, means acting normally to hold the feeler in rearward feeling position, and means actuated by the lateral displacing movement of the feeler when the weft is nearly exhausted to initiate replenishment of weft.
8. A feeler mechanism for looms having, in combination, a feeler supported for movement toward and from the front of the loom in a path inclined to the longitudinal axis of the shuttle and held from movement along the weft-carrier by engagement with the weft until the weft is nearly exhausted, means actuated by the lateral movement of the feeler along the weft-carrier when the weft is nearly exhausted for initiating replenishment of weft, and means acting as the feeler moves rearwardly after a detecting beat to return the feeler laterally to feeling position.
9. A feeler mechanism for looms having, in combination, a feeler support having a front guide and a rear guide, one of which is recessed transversely, a feeler movable toward and from the front of the loom rela-

tive to the support and adapted to be displaced transversely in the recessed guide of the support by impact when the weft is nearly exhausted and held from such trans-
5 verse displacement by engagement of the feeler and weft when a working supply of weft is present on a detecting beat, and a controller adapted to be moved transversely by the lateral movement of the feeler when
10 the weft is nearly exhausted.

10. A feeler mechanism for looms having, in combination, a feeler support having a front guide and a rear guide, one of which is recessed transversely, a feeler movable 15 toward and from the front of the loom relative to the support and adapted to be displaced transversely in the recessed guide of the support by impact when the weft is nearly exhausted and held from such trans-
20 verse displacement by engagement of the feeler and weft when a working supply of weft is present on a detecting beat, a laterally sliding controller adapted to be actuated by the transverse movement of the
25 feeler when the weft is nearly exhausted, the weft-hammer, a latch, and means connected to the controller for placing the latch and weft-hammer in operative relation when the feeler slides the controller transversely.

30. 11. A feeler mechanism for looms having, in combination, a feeler support, a feeler, guiding means on the support for sustaining the feeler in position to receive the impact of the weft or its carrier in a direction inclined to the longitudinal axis of the shuttle and permitting lengthwise and lateral movements of the feeler on its support, a spring 35 yieldingly acting to move the feeler rearwardly lengthwise on its support, said feeler being held from movement along the weft carrier by engagement with the weft until approaching exhaustion, and a controller movable in a direction transversely of the loom by the movement of the feeler along
40 the weft-carrier when the weft is nearly exhausted.

12. A feeler mechanism for looms having, in combination, a feeler support, a feeler mounted for lengthwise and lateral movements on its support by the impact of and held from movement along the weft carrier by engagement with the weft until approaching exhaustion thereof, a laterally sliding controller through which the feeler extends, 55 and means connected to the controller for initiating replenishment of filling when the controller is actuated by lateral movement of the feeler caused by impact thereon.

13. A feeler mechanism for looms having, 60 in combination, a feeler support, a feeler that directly receives the forward push of the weft and is moved thereby relative to the feeler carrier in a direction inclined to the longitudinal axis of the shuttle, and a
65 swiveled guide mounted on the feeler sup-

port and through which the feeler moves as it is pushed frontwardly on a detecting beat.

14. A feeler mechanism for looms having, in combination, a feeler support, a feeler that is moved relatively to the support in a direction inclined to the longitudinal axis of the shuttle by the impact of the weft, a guide relative to which the feeler is movable, and means for supporting the guide for rocking movement to permit angular 75 movement of the feeler member.

15. A loom having a feeler mechanism, comprising, in combination, a feeler supported to enter the shuttle in a direction inclined to the longitudinal axis of the weft-carrier 80 and movable in a direction inclined to the path of the lay, but being held from movement lengthwise along the weft-carrier by the weft on a detecting beat until approaching exhaustion thereof and then moving 85 along the weft carrier by the impact of said carrier, a toothed feeler tip freely pivoted to the feeler so as to accommodate itself to the surface of the weft and of the weft-carrier, and means actuated by the feeler to initiate 90 filling replenishment when the weft approaches exhaustion.

16. A feeler mechanism for looms having, in combination, a feeler supported for movement toward and from the front of the loom 95 in a path inclined to the longitudinal axis of the shuttle and held from movement along the weft-carrier under impact by engagement with the weft until the weft is nearly exhausted, means actuated by the 100 lateral movement of the feeler along the weft-carrier when the weft is nearly exhausted for initiating replenishment of weft, and a spring acting to move the feeler rearwardly after each detecting beat and also to 105 return the feeler laterally to normal feeling position after lateral displacement.

17. A feeler mechanism for looms having, in combination, a feeler with its tip in the path of the weft when in the box at the detecting end of the lay, said feeler being inclined to the longitudinal axis of the weft-carrier; a front guide slidably supporting the feeler near its front end and permitting the swing of said feeler, said guide being 110 located to one side of the fore and aft path of the feeler tip so that the impact of the weft on the feeler tip tends to swing the feeler; a slotted guide for the feeler near its rear end; a stud projecting from said 115 feeler; a stationary cam coöperating with said stud; a laterally movable controller having a slot through which the feeler freely passes during the normal running of the loom, said controller being moved laterally 120 when the feeler moves laterally due to the slipping of the feeler tip along the bared weft-carrier; a weft-replenishing train of mechanism brought into action by the lateral 125 movement of the controller; and a spring 130

acting upon said feeler to move it rearwardly during the normal running of the loom, and, after the lateral displacement of the feeler, also causing said stud to engage 5 and move along said cam, thereby restoring both the feeler and the controller to normal position.

18. A feeler mechanism for looms having, in combination, a feeler with its tip in the 10 path of the weft when in the box at the detecting end of the lay, said feeler being inclined to the longitudinal axis of the weft-carrier; a stationary feeler support upon which the feeler slides and swings at every 15 detecting beat of the lay; a stud projecting from said feeler; a stationary cam coöperating with said stud; a laterally movable controller having a slot through which the feeler freely passes during the normal running of 20 the loom, said controller being moved laterally when the feeler moves laterally due to the slipping of the feeler tip along the bared weft-carrier; a weft-replenishing train of mechanism brought into action by the lateral 25 movement of the controller; and a spring acting upon said feeler to move it rearwardly during the normal running of the loom, said controller being moved laterally when the feeler moves laterally due to the slipping of the feeler tip along the bared weft-carrier; a weft-replenishing train of mechanism brought into action by the lateral 30 movement of the controller; and a spring 35 acting upon said feeler to move it rearwardly during the normal running of the loom, and, after the lateral displacement of the feeler, also causing said stud to engage and move along said cam, thereby restoring both the feeler and the controller to normal position.

19. A feeler mechanism for looms having, in combination, a feeler with its tip in the 35 path of the weft when in the box at the detecting end of the lay, said feeler being inclined to the longitudinal axis of the weft-carrier; a stationary feeler support upon which the feeler slides and swings at every 40 detecting beat of the lay; a stationary cam coöperating with said feeler; and a spring acting upon said feeler to move it rearwardly during the normal running of the loom, and, after the lateral displacement of 45 the feeler, also causing the said feeler to engage and move along said cam, thereby being restored to normal position.

20. A feeler mechanism for looms having, in combination, a feeler with its tip in the 50 path of the weft when in the box at the detecting end of the lay, said feeler being inclined to the longitudinal axis of the weft-carrier; a front guide slidingly supporting the feeler near its front end and permitting the 55 swing of said arm, said guide being located to one side of the fore and aft path of the feeler tip so that the impact of the weft on the feeler tip tends to swing the feeler; a slotted guide for the rear end of the feeler; a laterally movable controller having a slot 60 through which the feeler freely passes during the normal running of the loom, said controller being moved laterally when the feeler moves laterally due to the slipping of 65 the feeler tip along the bared weft-carrier;

a weft-replenishing train of mechanism brought into action by the lateral movement of the controller; and a spring acting upon said feeler to move it rearwardly during the normal running of the loom.

70

21. A feeler mechanism for looms having, in combination, a feeler with its tip in the path of the weft when in the box at the detecting end of the lay, said feeler being inclined to the longitudinal axis of the weft-carrier; a front guide slidingly supporting the feeler near its front end and permitting the swing of said arm, said guide being located to one side of the fore and aft path of the feeler tip so that the impact of the weft 75 on the feeler tip tends to swing the feeler; a slotted guide for the feeler near its rear end; and a spring acting upon said feeler to move it rearwardly during the normal running of 80 the loom.

85

22. A feeler mechanism for looms having, in combination, a feeler with its tip in the path of the weft when in the box at the detecting end of the lay, said feeler being inclined to the longitudinal axis of the weft-carrier; a stationary support upon which said feeler both swings and slides and which permits the lateral displacement of the feeler tip along the bared weft-carrier; and a spring acting upon said feeler to move it 90 rearwardly during the normal running of the loom, and to restore it laterally to feeling position after displacement.

95

23. A feeler mechanism for looms having, in combination, a feeler with its tip in the 100 path of the weft when in the box at the detecting end of the lay, said feeler being inclined to the longitudinal axis of the weft-carrier; a stationary feeler support upon which the feeler both slides and swings; and a spring acting upon said feeler to move it 105 rearwardly during the normal running of the loom.

24. A loom having, in combination, a sliding and swinging feeler with a tip in the 110 path of the weft when in the box at the detecting side of the lay; a front guide slidingly supporting the front end of the feeler, said guide being offset laterally with respect to the feeler tip so that the weft encounters the tip along a path different from a parallel path intersecting said guide whereby the impact of the weft on the feeler tip tends to swing the feeler laterally; a transversely recessed rear guide through 115 which the feeler passes; a spring which moves the feeler arm rearwardly, and a train of mechanism which is brought into action as the result of the transverse slip of the feeler.

120

25. A loom having, in combination, a sliding and swinging feeler with a tip in the path of the weft when in the box at the detecting side of the lay; a front guide slidingly supporting the front end of the feeler, 125

130

said guide being offset laterally with respect to the feeler tip so that the weft encounters the tip along a path different from a parallel path intersecting said guide whereby the impact of the weft on the feeler tip tends to swing the feeler laterally; and a transversely recessed rear guide through which the feeler passes.

26. A feeler mechanism for looms having, 10 in combination, a side slipping sliding and swinging feeler with its feeling tip offset laterally with respect to the body of the feeler, said feeler moving forwardly and backwardly during the normal running of the loom and slipping laterally under the impact of a bared weft carrier; a stationary support upon which said feeler moves both during the normal running of the loom and when it slips laterally; and a single spring

which acts upon said feeler to move it rearwardly upon said support during the normal running of the loom, and also to move it laterally upon said support to its normal position after its side slip. 20

27. A feeler mechanism for looms having, 25 in combination, a side slipping sliding and swinging feeler with its feeling tip offset laterally with respect to the body of the feeler, said feeler moving forwardly and backwardly during the normal running of 30 the loom and slipping laterally under the impact of a barrel weft carrier; and a stationary support upon which said feeler moves both during the normal running of the loom and when it slips laterally. 35

In witness whereof, I have hereunto signed my name,

EDWARD S. STIMPSON.

It is hereby certified that in Letters Patent No. 1,309,226, granted July 8, 1919, upon the application of Edward S. Stimpson, of Hopedale, Massachusetts, for an improvement in "Feeler Mechanism for Looms," an error appears in the printed specification requiring correction as follows: Page 7, line 32, claim 27, for the word "barrel" read *bared*; and that the said Letters Patent should be read with this correction therein that the same may conform to the record of the case in the Patent Office.

Signed and sealed this 22d day of July, A. D., 1919.

[SEAL.]

Cl. 139--85.

R. F. WHITEHEAD;
Acting Commissioner of Patents.
